UNITED STATES PATENT OFFICE.

JOSHUA PERKINS, OF DANIELSONVILLE, CONNECTICUT.

TRUSS.

SPECIFICATION forming part of Letters Patent No. 416,739, dated December 10, 1889.

Application filed October 7, 1889. Serial No. 326,172. (No model.)

To all whom it may concern:

Be it known that I, JOSHUA PERKINS, a citizen of the United States, residing at Danielsonville, in the county of Windham and State of Connecticut, have invented certain new and useful Improvements in Trusses; and I do hereby declare that the following is a full, clear, and exact description of the same, reference being had to the annexed drawings, making a part of this specification, and to the letters of reference marked thereon.

This invention relates to certain new and useful improvements in trusses; and it has for its object to provide an improved truss which shall be comfortable to the wearer, and which will be retained in its proper position, notwithstanding any motion of the body.

The invention consists in the peculiar combinations and the novel construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a perspective view of my improved truss with the attaching-straps connected therewith. Fig. 2 is a central cross-section through the pad and its attached parts. Fig. 3 is a perspective view of the pad portion on an enlarged scale, showing the manner of attaching the straps thereto, so that they can freely move thereon.

Like letters of reference indicate like parts throughout the several views.

Referring now to the details of the drawings by letter, A designates the body of the pad or truss, which may be composed of any suitable material adapted for the purpose and provided with the central enlargement a, as shown in Fig. 2.

B is a plate or disk, of metal or other suitable material, (in some instances it might be celluloid,) from which extend the arms C, shown as three in number, although the number might be varied under some circumstances. The outer ends of these arms are

turned under to form eyes or loops b, in which is secured the wire ring D by bending the said ends after the ring has been inserted in the loops or eyes, thus rendering the ring easily detachable when occasion may require. This plate or disk B is held to the truss or pad A by means of the screw E, which passes loosely through a hole in the plate and screwed into the center of the pad, as shown clearly in Fig. 2. This allows the plate and its arms to turn freely on the said screw as a pivot, a washer or plate being provided upon each side of the said plate B, as shown in Fig. 2, and designated by the letters F and G, to serve as a guide for the plate B, and prevent wear on the truss or pad.

The ends of the perineal and sustaining body-straps I and J are connected with the wire ring D, as shown more clearly in Fig. 3, in such a manner that the said straps are free to move or slide on the rim or ring D, which, in connection with the revolving motion of the central plate and its arms provides for the retaining of the truss or pad in its desired place notwithstanding the motion of the body of the wearer.

The parts are easily assembled or detached, when necessary, for the purpose of cleaning or otherwise, and in practice the truss has proved most efficient.

What I claim as new is—

1. In a truss, the combination, with the pad, of the revolving plate thereon, the ring connected to move with said plate, and the straps connected with said ring and free to slide thereon, substantially as described.

2. In a truss, the combination, with the pad and the revolving plate thereon, and provided with the arms, as shown, of the ring held by said arms, and the straps attached to said ring and free to slide thereon, substantially as and for the purpose specified.

In testimony that I claim the above I have hereunto subscribed my name in the presence of two witnesses.

JOSHUA PERKINS.
